UNITED STATES PATENT OFFICE.

SANFORD A. LARSON, OF DENVER, COLORADO.

TOOL FOR CUTTING THREAD.

1,003,922.

Specification of Letters Patent. Patented Sept. 19, 1911.

Application filed May 18, 1911. Serial No. 627,951.

To all whom it may concern:

Be it known that I, SANFORD A. LARSON, a citizen of the United States, residing at Denver, in the county of Denver and State 5 of Colorado, have invented certain new and useful Improvements in Tools for Cutting Thread; and I do hereby declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

This invention relates to new and useful improvements in devices for cutting threads upon pipes, which may be inconveniently located for the employment of the usual dies 20 for this purpose.

The invention comprises various details of construction and combinations and arrangements of parts which will be herein-after fully described and then specifically 25 defined in the appended claim.

I illustrate my invention in the accompanying drawings, in which:—

Figure 1 is a side elevation showing the application of my device in readiness for 30 use. Fig. 2 is a central longitudinal sectional view, and Fig. 3 is an end view.

Reference now being had to the details of the drawings by letter, A designates a shell which is adapted to telescope within the 35 pipe upon the circumference of which the threads are to be cut. Said shell has slots A' formed therein so that the part thus slotted may be expanded for the purpose of frictionally holding the device within a 40 pipe.

In Fig. 1 of the drawings, I have shown in dotted lines the pipe, designated by letter B, within which the device is held. A flanged plug D is fitted in one end of the 45 shell, and E is a sleeve having a threaded portion E' upon the circumference thereof and adapted to fit the threads of a die, designated by letter F. Said shell is made preferably of a soft metal and a screw H is 50 passed through registering apertures in the

sleeve and shell and engages a threaded hole in the plug D. A screw, designated by letter K, passes through the plug and has a head K' and is threaded at K² for the reception of the expanding nut L which is conical 55 shaped and is adapted to contact with the split end of the shell and so arranged that, when the screw is turned, the end of the shell may be expanded to frictionally engage the inner surface of the pipe upon the 60 circumference of which the threads are to be formed.

In adjusting the device for use, the die is threaded upon the sleeve and the shell inserted within the pipe and the screw turned 65 to cause the pipe to be held by friction in place. A die F may be turned by a wrench or any other suitable tool and the threads upon the sleeve serve as feeding means for feeding the die over the tread on to the 70 circumference of the pipe.

It will thus be seen that, by the provision of a device as shown and described, a simple mechanism is afforded whereby threads may be cut upon the circumference of a pipe 75 which may be located in an inaccessible place where the ordinary cutting die with rod or handle connections could not be well used.

What I claim to be new is:—

A thread cutting device comprising a shell with split end, a flanged plug fitted within the shell and centrally apertured, a headed screw passing through the plug, an expanding nut upon the screw forming means for 85 holding the shell within the plug, a sleeve telescoping over said shell and having a portion thereof threaded and an unthreaded portion, the end of which abuts against the flange of said plug and its circumference 90 flush with the edge of the flange, and a screw passing through registering apertures in said sleeve and shell and engaging a hole in the plug.

In testimony whereof I hereunto affix my 95 signature in the presence of two witnesses.

SANFORD A. LARSON.
